UNITED STATES PATENT OFFICE.

WILLIAM D. DICKEY, OF NEW YORK, N. Y.

HYDROCARBON-FURNACE.

SPECIFICATION forming part of Letters Patent No. 234,395, dated November 16, 1880.

Application filed September 1, 1880. (No model.)

To all whom it may concern:

Be it known that I, WILLIAM D. DICKEY, of the city, county, and State of New York, have invented certain new and useful Improvements in Hydrocarbon-Furnaces, of which the following is a specification, reference being had to the accompanying drawings, forming part of the same, in which—

Figure 1 is a vertical section of a steam-boiler with my improved attachments (partly in section) for generating steam connected therewith, and Fig. 2 is a central sectional view (or partly in section) of one of the said attachments detached from its connection with the boiler.

My invention relates to the construction and arrangement of a steam-boiler and connections, whereby pulverized or fluid fuel may be advantageously burned for the generating of steam and other purposes.

A represents a steam-boiler, A' being its tubular flues, A² its fire-place, A³ the steam-dome, and A⁴ an inclined bridge or abutment in the fire-place, whereby the flame is deflected upward, and a combustion-chamber, A⁵, is formed behind the bridge in front of the flues.

B is a steam-superheater, consisting, preferably, of metal pipe, coiled or otherwise bent upon itself, (so as to get a considerable length of it within the fire-place,) arranged within and preferably at the top of the fire-place A², where it may be heated by the fire in the fire-place.

B' is a pipe leading from the steam-space of the boiler, preferably the dome A³, to the superheater, and provided with a steam-cock, a.

B² is a steam-pipe leading away from the superheater B to the steam-discharge nozzle C, to be more particularly described presently.

D is a water-tank, and D' a pipe leading from said tank into pipe B', and provided with a water-cock, a'.

E is a conical hood or air-conductor attached to the front of the boiler, so as to inclose the doorway in front opening into the fire-place.

The other end is preferably provided with a revolving damper or register, whereby it may be closed or opened for the admission of air. Openings b b' are also made in the body of the hood near the boiler, provided with a door or damper.

E' is a conical air-conductor, projecting around the doorway or front opening of the fire-place inward toward the fire-place, that serves to deflect the air that enters the openings b b' into the flame, while it also acts to cause the steam that is discharged from C, as it rushes into the fire-place, carrying with it the fuel, to draw air in through the said openings b b'.

C' is a steam and air discharge nozzle, arranged within the hood E, as shown in Fig. 1.

C is a steam-nozzle arranged concentrically within the nozzle C', and C² is the steam-entrance passage to nozzle C, fitted for connection with steam-pipe B².

C³ is a similar passage for connection with said pipe B² when it is desired to make such connection on the top of said nozzle C, or it may be fitted with a cap to be removed and permit the steam entering through C² to be discharged for the purpose of blowing out any sediment or other obstruction that may get into C.

C⁴ is an air-entrance passage, and C⁵ an air-pipe leading into the same.

F is an air-blower, and C⁶ an air-conductor leading therefrom, with which said pipe C⁵ connects. The conductor C⁶ opens into the open air, as at e, and is provided with two air-cocks, a² and a³, one on each side of the pipe C⁵.

G is a fuel-discharging nozzle, and G' a pipe leading to and connecting therewith. When fluid fuel is to be burned this pipe G' is connected with and leads from a can or tank, H, containing the fuel, which may be petroleum or any of the liquid hydrocarbons, and is provided with a cock, a⁴. When pulverized fuel is to be used the nozzle G is to be connected with a blower by a suitable conductor and provision made for introducing said fuel into the blower or conductor, so that it may be impelled into and through the said nozzle G.

These nozzles C' and G are arranged relatively to each other with their axes at an angle, as shown in the drawings, so that steam and air discharged from C' will pass across the end of G, whereby the fuel, whether fluid or pulverized, as it issues from G, will be atomized if fluid, or scattered if pulverized, and impelled into the fire-place or combustion-chamber.

The nozzle C projects across air-entrance passage C⁴, whereby steam issuing from C into and through C' will act to draw air in through the passage C⁴. The nozzles C and G are each 5 preferably provided with a spindle-valve, h h', for regulating the discharge from the nozzles, that are adjustable by means of screw-threads in the bodies of the spindles, that work in female screws in or connected with the rear ends 10 of the nozzles, as shown plainly in Fig. 2.

The nozzles C' and G are preferably made of a single piece of metal, being connected by a web, G². This insures their continued proper 15 relative position and adjustment. The nozzle C is made of a separate piece, screwed into C', as shown in Fig. 2.

It is absolutely essential for producing the desired result that G and C' shall open into the atmosphere, so as to discharge the steam, 20 air, and fuel directly into the combustion-chamber, without the interposition of any inclosing conductor between them and said chamber. I have found by experiment that any such conductor prevents complete combustion and lessens the auxiliary aid to combustion derived from decomposition of the steam.

Of course the particular form or construction of the steam-generator is not important 30 so long as it is adapted to have combined with it the attachments described, and to the generation of steam therein by the fire made by the combustion of the fuel discharged from the nozzle G and impelled into the combustion-chamber by the steam and air issuing from 35 the nozzle C'.

The operation of the described apparatus is as follows: For the purpose of starting the fire, cock a being closed, the cock a⁴ is opened, 40 allowing the fuel to flow down from the tank H into the nozzle G. At the same time the blower F is set in motion with cock a² shut and cock a³ open. The current of air that will be thereby discharged from or through the nozzle C' will atomize or scatter, as the case may be, the fuel issuing from G and impel it into the fire-place A²—the combustion-chamber. This operation is to be continued until a head 45 of steam is raised in the steam-boiler. When this result is attained the blower may be stopped and the cock a² opened. The cock a being then also opened, the steam from the boiler will pass through the pipe B' into and through the superheater B, and thence through 50 B² to the nozzle C and out of nozzle C', drawing after it air through C⁴, whereby the fuel issuing from G is driven forward into the fire-place and atomized or scattered into the combustion-chamber. The combustion taking place 55 in the presence of superheated steam intimately commingled with the comminuted fuel, said steam will be, to a greater or less extent, decomposed, and the resulting hydrogen will act as an auxiliary fuel.

60 A supply of air to support the combustion

is insured by the action of the steam issuing from nozzle C, drawing the air in through C' and impelling it, with the steam, through C'.

The superheater B will be heated upon starting the fire by the action of the blower some 70 time before a head of steam can be raised in the boiler. As soon as it becomes sufficiently heated to superheat the steam the cock a' may be opened and water from the tank D allowed to flow down through pipe D' into B', and so 75 into the superheater B, where it will be quickly converted into superheated steam, which will be discharged from the nozzle C. When this result is reached the blower may be stopped, the cock a³ closed, and cock a² opened, as the operation will then be continued and the discharge 80 into the combustion-chamber secured until a head of steam is raised in the boiler.

The bridge-wall A⁴ serves the purpose of deflecting the flame and heat upon the superheater and the surface of the boiler over the fire-place, thereby insuring the desired superheating of the steam; also, becoming itself intensely heated, it will instantly ignite the inflowing current of fuel, if for any reason the flame should become extinguished while the apparatus is in operation. It is important that the bridge should be inclined backward, as represented, in order to give the flame and heat the proper direction, and not too much obstruct 95 their movement toward the fire-flues.

When, in starting the fire, air is forced by the blower into the nozzle C', it will, unless prevented, back up into the nozzle C, and the force of the current of the air from the nozzle 100 C' be thereby destroyed or materially diminished.

By running in the spindle-valve h' the nozzle C may be closed while the blower F is in operation, to be opened by running back said 105 spindle when steam is raised and let on to said nozzle C.

When the apparatus described is in full operation with highly-superheated steam acting to atomize or scatter and impel the fuel 110 into the combustion-chamber, and at the same time a rapid current of atmospheric air is drawn in by the steam to support combustion, rapid combustion is effected and a very intense heat 115 produced.

What I claim as my invention, and desire to secure by Letters Patent, is—

1. The combination, with the fire-space of a steam-boiler, of a steam-superheater located in said fire-space, a steam-pipe, B', leading 120 from the steam-space in the boiler to said superheater, provided with a cock, a, the nozzle C, a steam-pipe, B², leading from said superheater to said nozzle, the nozzle G, arranged relatively to the nozzle C, as shown and described, the fuel-holding tank H and conductor G', leading from the same to the nozzle G, provided with a cock, a⁴, the nozzle C' and air-inlet passage C⁴, arranged relatively to the nozzle C, as shown and described, the said 130

nozzles C' and G being arranged relatively to the fire-space to discharge steam, air, and fuel directly into said fire-space without any intervening conductor, as and for the purpose described.

2. The combination, with a fire-place, of the nozzles C, C', and G, the hood E, within which the said nozzles are located and by which they are supported, so that liquid fuel issuing from G will be atomized and projected by steam issuing from C directly into said fire-place without passing through any intervening conductor, all as and for the purpose described.

3. The combination, with a fire-place, of the nozzle C and nozzle C', the former located concentrically within the latter, as described, an air-inlet passage to C', a steam-conductor leading into C, the nozzle G, arranged relatively to the nozzle C', as described, and a fuel-supply conductor leading into G, whereby liquid fuel issuing from G may be atomized and projected into the fire-place by steam issuing from C, and at the same time air drawn into the nozzle C' by the action of the steam will be mingled with the inflowing current of steam and fuel before they reach the combustion-chamber in the fire-place, all as and for the purpose described.

4. The combination, with the fire-place A² of a steam-boiler, of a steam-superheater B, located in the upper part of said fire-place, the steam-nozzle C and fuel-nozzle G, arranged as described, whereby fluid fuel issuing from G may be projected into the fire-place by steam issuing from C, and the backwardly-inclined bridge-wall A⁴, whereby the flame made by the combustion of said fuel will be deflected onto said superheater, or toward the upper part of said fire-place, as and for the purpose described.

5. The combination of the boiler A, fire-place A², steam-superheater B, steam-pipe B', provided with stop-cock a, water-tank D, and

pipe D', leading into pipe B' and provided with stop-cock a', all as and for the purpose described.

6. The combination of a fire-place, a steam-superheater located in said fire-place, a water or steam supply and pipe leading therefrom to said heater, the nozzle G, and a pipe leading to a liquid-fuel supply, the nozzle C', arranged relatively to the nozzle G, as described, the air-blower F, and air-conductor C⁶, leading from said blower to the nozzle C', and provided with a stop-cock, a², all as and for the purpose described.

7. The nozzle C', blower F, conductor C⁶, leading from the said blower and provided with stop-cock a³, the pipe C⁵, leading from C⁶ to said nozzle C', the open end c of said conductor, and stop-cock a² between the pipe C⁵ and said open end, all combined to operate as and for the purpose described.

8. The nozzle C', nozzle C, located concentrically within C', the blower F, and conductor leading from said blower to the nozzle C', the nozzle C being provided with the spindle-valve, whereby the said nozzle may be closed when the said blower is in operation to prevent the air from backing into said nozzle C, and may be opened when the blower is stopped and steam let into said nozzle C, all as and for the purpose described.

9. The combination, with the fire-place A², of the hood E, provided with the conical conductor E', projecting toward the fire-place, air-openings b b', and the nozzles C and G, arranged within and supported by said hood, and the pipe-connections of said nozzles described, all as and for the purpose specified.

Witness my hand this 31st day of August, 1880.
